CONTAINER.

Edwin L. Mott, St. Louis, Mo.

Application October 20, 1938, Serial No. 235,984

4 Claims. (Cl. 206—44)

This invention relates to certain new and useful improvements in multiple-use containers, adaptable either for shipping or display purposes and has for its primary objects the provision of a container of the type stated which is simple and economical in form, structure, and manipulation, which is substantially cut away along its side walls in the provision of a relatively large display opening, which is unusually rugged and structurally strong and durable when assembled for shipping purposes, which may be quickly, simply, and conveniently converted from shipping form or arrangement to display form or arrangement, and which is highly satisfactory and efficient in the performance of its stated functions.

And with the above and other objects in view, my invention resides in the novel features of form, construction, arrangement, and combination of parts presently described and pointed out in the claims.

In the accompanying drawings (3 sheets),

Figure 1 is a perspective view of a container of my invention in closed, shipping assembly;

Figure 2 is a transverse sectional view of the container, taken approximately along the line 2—2, Figure 1;

Figures 3 and 4 are perspective views of the container in partially opened positions;

Figure 5 is a perspective view of the container in fully opened or display position;

Figure 6 is a plan view of a die-cut box blank for the formation of a modified form of container constructed in accordance with and embodying my present invention;

Figure 7 is a perspective view of the modified form of container in partially erected position;

Figure 8 is a perspective view, partially broken away and in section, of the modified form of container; and

Figure 9 is a transverse vertical sectional view of the modified form of container.

Referring now more in detail and by reference characters to the drawings, which illustrate a preferred embodiment of my invention, the finished container is preferably, though not exclusively, in the form of a rectangular box-like structure of any size and dimensions for snugly housing the particular merchandise, as best seen in Figure 1, and embodies in its structure two essential members, that is to say, a container-shell A and a so-called closure sham B.

The container-shell A, in turn, integrally includes a rectilinear rear wall 1, a rectilinear front wall 2 of substantially lesser height than the rear

wall 1, and opposed parallel side walls 3, 4, which latter, along their upper margins 5 are suitably cut-away and curved forwardly and downwardly in flushwise relation at their ends, respectively, with the upper margins of the front and rear walls 1, 4, as best seen in Figures 1 and 2.

Along its upper margin, the rear wall 1 is integrally provided with a hingedly connected top-wall or cover-member 6, which at its opposite margin has an integral hingedly connected tuck-flap 7 substantially shorter than the height of the rear wall 1. Suitably located in the cover 6, is a pair of endwise aligned score-lines 8, which extend inwardly from and preferably at right angles to the opposed parallel side margins 9 of the cover 6 and at their inner extremities terminate respectively at the opposite ends of a preferably U-shaped cut-out 10 forming a so-called "push-out," such that the top-wall or cover member 6 may be transversely folded or bent upon itself, when the carton is in merchandise display condition, as shown in Figures 3 and 5, in the provision of an upstanding advertising back-card C. It may be pointed out in this connection that the distances x , x' , between the hinge-lines 8 and the front and rear margins, respectively, of the top-wall 6 are unequal, the distance x preferably being somewhat smaller than the distance x' , as best seen in Figure 1, for purposes presently more fully appearing. It should also be noted that the lateral margins 11 of the top-wall closure or tuck-flap 7 are inclined angularly inwardly, also as best seen in Figure 1 and for purposes presently more fully appearing.

Along their lower margins, the shell-walls 1, 2, 3, 4, are integrally provided with inwardly swinging flaps 12, which, in turn, are secured together in overlying bottom-forming relation either by gluing, interlocking, or in any other conventional manner, all as best seen in Figure 2 and for purposes presently more fully appearing.

The so-called closure-sham B integrally includes a front wall 13 and two parallel opposed side-wall members 14, 15, of identical shape, the walls 14, 15, being provided along their upper margins with inwardly folding narrow flaps 16 having forwardly presented lateral margins 16' spaced slightly away from the vertical plane of the inner face of the front wall 2. At their rearwardly presented margins 17, the side walls 14, 15, are inclined angularly forwardly, and at their lower margins 18, being curved upwardly and rearwardly preferably in a shape complementary to the shape of the margins 5 of the container-shell side-walls 1, 3, 4.

It may be stated in this connection that the length of the front member 13 of the sham B is equal to the transverse distance between the inner faces of the container-shell side-walls 3, 4, and the length of the side-members 14, 15, along the upper margins thereof is equal to the transverse distance between the inner faces of the container-shell front and rear walls 1, 2, all for snug-fitting wall-supplementing disposition within the container-shell A, as best seen in Figure 3.

In use, the container-shell A and the sham B are assembled, as shown in Figure 3, and merchandise snugly packed therein. The top-wall or cover 6 is then folded closurewise down into overlying relation upon the inwardly turned sham flaps 16 and the cover-flap 7 is tucked in between the inner face of the sham front wall 13 and the forwardly presented lateral margins 16' of the sham flaps 16, as best seen in Figures 1 and 2. In this condition, the merchandise is securely housed within an entirely closed and walled container of even greater structural strength than the ordinary rectangular cardboard box. By reason of the fact that the container-shell cover-flap 7 is interlockingly held between the sham front-wall 13 and the container-shell front-wall 2, as best seen in Figure 2, the entire structure will be held in rigid container-forming relationship. Furthermore, since the sham side-walls 14, 15, are angularly relieved along their lateral margins, the sham B will not bind against the container-shell side-walls 2, 3. Similarly, the sham side-members or walls 14, 15, being angularly relieved along their lateral margins 17, will not bind against the container-shell rear-wall 1 except adjacent the upper margin thereof. Thus arranged, the container and enclosed merchandise may safely be shipped or stored.

When the retail merchant desires to place the housed merchandise on counter sale or display, the cover 6 is folded up and bent about the score-lines 8 and the sham B entirely removed, as shown in Figure 4, the cover-flap 7 being finally tucked down between the merchandise and the inner face of the container-shell rear-wall 1, the container then forming an unusual open-topped display tray in which the merchandise is clearly and visibly presented to the prospective purchaser, as best seen in Figure 5. In this connection, it may be noted that, by reason of the fact that the distances x, x' , are unequal, as previously stated, the forward margin m of the cover 6 will not be coincident with the rearward margin m' thereof, effectively preventing either or both of the margins from having hinge-action, and consequently holding the cover-formed advertising card C in upright or other adjusted position.

I may also provide a main or container-shell A' of one-piece "fold-up" construction comprising a unitary blank 19 scored and die-cut substantially along the lines shown in Figure 6, being divided by the score lines 20, 21, 22, 23, 24, 25, into a front tab 26, an inner front wall member 27, an outer front wall member 28, a bottom 29, a back wall 30, a top or cover member 31, and a closure-flap 32.

Formed integrally and extending transversely outwardly from the bottom wall 29 and being separated therefrom by the transverse score lines 33, 34, are side wall members 35, 36, substantially similar in shape to the side walls 3, 4, of the container-shell A, above described. Extending forwardly from the walls 35, 36, are integral front wall flaps 37, 38, respectively separated from the

side walls 35, 36, by the score lines 39, 40, which are coincident with the score line 22. Extending rearwardly from the side walls 35, 36, are erection flaps 41, 42, separated from the side walls 35, 36, respectively, by the score lines 43, 44, which are coincident with the score line 23.

Along their rearwardly presented margins, the erection flaps 41, 42, are each provided with key-lock tabs 45, 46, for co-operative engagement with appropriately located slots 47, 48, formed in the rear wall member 30.

The top member 31 is provided within its area with a U-shaped die-cut 49 connected at its ends by short score lines 50 to the outer side margins of the top member 31 in the provision of a fold-up back member C', substantially identical in shape and function with the back member C of the container-shell A previously described, all as best seen in Figure 6.

In setting up the container for actual use, the box blank 19 is folded about its various score lines substantially in the manner shown in Figure 7, the erection flaps 41, 42, being brought up into overlying facewise engagement upon the rearwardly presented face of the back wall 30 and the key-lock members 45, 46, inserted through the slots 47, 48, respectively, thus holding the back wall 30, the side walls 35, 36, and the bottom wall 29 in upright container-formation. The front wall flaps 37, 38, of the side walls 35, 36, are turned inwardly and the outer front wall member 28 folded up into facewise engagement along its inwardly presented face with the outwardly presented face of the inwardly folded front wall flaps 37, 38. The inner wall member 27 is thereupon folded downwardly into facewise engagement with the inwardly presented face of the front wall flaps 37, 38, and held in upright position by frictional engagement along its vertical side margins with the inner faces of the side walls 35, 36, and by frictional engagement between the front flap 26 and the upper face of the bottom 29 in the formation of the container-shell A', which is substantially similar to the container-shell A, previously described, all as best seen in Figures 8 and 9.

In use, a sham member B may be inserted into the container-shell A', substantially in the same manner as above described, and the cover member 31 folded thereover, the cover flap 32 being tucked in between the inner face of the sham front wall 12 and the forwardly presented lateral margin 16' of the sham flaps 16, all as best seen in Figure 9.

Thus, by my invention, I provide a unique, inexpensive, simple, durable convertible container, which is an entirely self-supporting structure strong and rigid when arranged for use as a shipping container and which, at the same time, may be simply, conveniently, and quickly converted into a display-container without removing the contained merchandise or shifting such merchandise into different positions, and in which, when arranged for display purposes, the contained merchandise is displayed in an extremely and attractive sales compelling manner.

It will be understood that changes and modifications in the form, construction, arrangement, and combination of the several parts of the container may be made and substituted for those herein shown and described without departing from the nature and principle of my invention.

Having thus described my invention, what I claim and desire to secure by Letters Patent is,—

1. A multiple-use container comprising a shell

having a rear wall, a front wall substantially shorter than the rear wall, side walls connecting the front and rear walls, and having upper margins contoured for connecting the upper margins of the front and rear walls, a cover-member, in combination with a removable three-sided wall-member having opposed side wings, the bottom margins of which are of substantially the same contour as the upper margins of the shell side-walls, and a front wall of substantially the same size and shape as the rear wall for cooperation with the shell in evenly supporting the cover-member when in closed position.

2. A multiple-use container comprising a shell having a bottom member, opposed parallel side walls marginally connected to opposed transverse margins of the bottom, a rear wall marginally connected to a longitudinal margin of the bottom member, a flap hingedly connected along the rear margin of each of the side walls having means for releasable engagement with the back wall, an inwardly folding flap hingedly connected along the front margin of the side wall, a two-panel front wall member foldable over and into frictionally retentive engagement with said inwardly folding flaps and having a marginal retaining flap foldable inwardly for frictional engagement with the bottom wall for simultaneously holding the front portion of the side walls erect and forming a front wall for the container, said front wall being substantially smaller in height than the back wall, and a three-walled sham member removably mounted in the shell and having a front wall substantially identical in size and shape with the back wall and side walls being disposed facewise abutting engagement respectively with the inner faces of the side walls and marginal engagement with the line of junction between the retainer flap and the front-wall flap in the formation of a completely rectilinear container. 40

3. A container comprising a shell having a front, rear, and two side walls, said front and side walls being reduced in height to provide a low-front display tray, a cover hinged marginally to the rear wall, and a removable three-wall sham integrally including a center wall substantially the same shape and dimensions as the rear wall and side walls marginally cut away at their lower and rearward margins for engagement with the bottom wall only along the forward portion thereof and for engagement with the back wall only at the upper portion thereof.
4. A multiple-use container comprising a shell having a bottom wall, a rear wall, a front wall of lesser height throughout than the rear wall, opposed side walls partially of lesser height than said rear wall, and a cover-member marginally hinged to the upper margin of said rear wall, in combination with a sham sized for snug-fitting removable disposition within the shell and including a front wall having a height substantially the same as that of said shell rear wall being adapted to fit marginally upon the bottom wall and having a free edge for underlying supporting engagement with the cover when in closed position, the sham having opposed side walls shaped for container-wise completing the shell side walls and provided along their upper margins with inturned flaps disposed substantially in the same plane as the front-wall free margin for supporting engagement with the cover, and being, along their forward transverse margins, spaced slightly from the inner face of the front wall, said cover further having a front flap end-wise insertable between the inner face of the sham front wall and the forward transverse margins of the sham flaps when the cover is closed. 35

EDWIN L. MOTT.
